[57] CLAIM

The ornamental design for a cluster of glazed ceramic tiles, substantially as shown.

DESCRIPTION

FIG. 1 is a perspective view of a single tile of the unit shown in FIG. 5;

FIG. 2 is a top plan view of the tile shown in FIG. 1;

FIG. 3 is a side view thereof;

FIG. 4 is a bottom plan view thereof; and

FIG. 5 is a top plan view of a cluster of glazed ceramic tiles showing my new design.

Fig. 1.

Fig. 2.

Fig. 3.

Fig. 4.
